UNITED STATES PATENT OFFICE.

LOUIS ANNIN AMES, OF NEW YORK, N. Y.

FLAG HOLDER AND SUPPORT THEREFOR.

Application filed July 1, 1927. Serial No. 202,804

This invention appertains to improvements in supporting means for flags or the like.

An object of the invention is to provide in conjunction with the holder for a flag or the like, a clamping device adapted for attachment to a post whereby the holder is disposed in service on the post in a position to receive the flag or other supported member and to support and display the same.

Another object of the invention resides in the provision of a construction of the above character in which the holder may be adjusted on the clamping device and may assume any desired position on the periphery of the post.

A further object of the invention is to produce an arrangement whereby any desired number of holders may be attached to the post by the clamping device so that a plurality of flags or like devices may be displayed on the post.

The invention further aims to improve the construction of the holder with a view to rendering it very simple and efficient and to provide a holder for firmly and securely maintaining the flag or other supported member in service position and for permitting the ready attachment and detachment of the supported member.

The holder is in many respects similar to that disclosed in my pending application for patent, Serial No. 174,812, filed March 12, 1927, but the construction has been somewhat changed in order to adapt the holder for the use in mind.

Other objects and advantages of this invention will appear as the description proceeds.

40 In the drawings:

Figure 1 is a fragmental view of a post showing the disposition of a plurality of holders thereon and the manner in which the invention is carried out in practise;

45 Figure 2 is a sectional plan view of a detail of the invention;

Fig. 3 is an isolated side elevational view partly in section of the preferred form of holder, showing the supported member in dotted lines;

50 Figure 4 is a side elevational view of a fragment of the construction, the view being taken looking upward at Figure 2; and

55 Figure 5 is a front elevational view looking at Figure 3 from the right.

Referring now more particularly to the

drawings in which is shown the preferred embodiment of the invention and to the details of which I do not intend to be confined, the invention is illustrated as exemplified in a construction which comprises a post 10, on which is disposed a holder for a flag or the like, the holder being generally indicated by the numeral, 11. One or more of such holders may be arranged on or around the post. Each holder comprises a flat portion 12 adapted for disposition against the side of the post and to be clamped in place thereon and attached thereto.

The clamping means preferably comprise a band 13 extending around the periphery of the post and placed under tension thereon, said band preferably extending through a member 14 in the nature of a keeper struck out from the flat portion 12 of the holder. The band being under tension is thus maintained in service on the post and serves to maintain the flat portion 12 of the holder flat against the periphery of the post.

Any desired or suitable means may be employed for placing the band under tension. In the particular embodiment selected for illustration, the free ends of the bands terminate adjacent each other and each has an L-shaped member 15 with a slot 16 through which the respective end of the band passes and is bent back, thereby securing the L-shaped member thereto. The L-shaped members are drawn together by means such as a bolt 17, which, when tightened, serves to place the band under tension and to firmly maintain it in service position at the desired place on the post.

By reference to Figures 3 and 5, it will be seen that in the preferred embodiment of the invention the flat portion 12 of the holder merges into a portion 18 preferably extending at an acute angle to the flat portion. The portion 18 terminates in an approximately rightangular portion 19 which in turn terminates in a portion 20 extending back on the portion 18 and having a free end 21 which is preferably slightly curved. The portion 19 has an opening 22 through which the end of a flag or other supported member is adapted to be inserted. This supported member is firmly and resiliently held by the resilient action of the portion 20 which forces it firmly against the side 18 of the holder. The provision of the curved part, 21, serves to distribute the resilient action of the member 20 uniformly over a

considerable length of the supported member and the force is not concentrated at a single point.

The portion 20 also preferably has a slot 23 into which the supported member partially fits when placed in the holder. The purpose of the slot 23 is to prevent turning, twisting, or wiggling of the supported member when inserted in the holder. The slot 10 is smaller in width than the supported member throughout the major portion of its length but has a slightly enlarged part 23a at its bottom into which the tip of the supported member extends.

15 In conjunction with this construction a catch or the like 24 may be used, one end of which has an eyelet 25 extending through a perforation near the top of the part 12 and the other end has a hook 26 adapted for 20 cooperation with a slot 27 in the part 19, the catch serving to prevent the parts 12 and 18 of the holder spreading apart and the holder sagging under the weight of the supported member. Of course, any other 25 desired member or means may be employed to obtain this result.

The use of a band surrounding the post and the method of attaching the flag holder to the band enables the holder to be slid on 30 the band and to be adjusted and placed at any desired point on the periphery thereof and any desired number of holders may be arranged on the band. The specific construction of holder used permits easy and ready 35 attachment or detachment of the supported members or flags at will and in addition provides a very cheap, economical and efficient device. Other types of holders may be employed, however, in the practice of the invention and I do not confine myself to the 40 specific construction disclosed nor to any details described above.

Various alterations and changes may be

made in the structure and arrangement disclosed without departing from the spirit of 45 the invention and I desire to be limited only by the state of the prior art and the scope of the appended claims.

Having thus fully described my invention, what I claim as new and desire to secure by 50 Letters Patent is:

1. A holder of the class described comprising a substantially straight portion, a portion extending back on said straight portion and adapted to clamp a supported member against the straight portion, the second portion having a slot for the partial accommodation of the supported member, and a portion connecting the aforesaid portions, said portion having an opening through 60 which the supported member extends.

2. A holder of the class described comprising a flat portion, means for attaching said flat portion in service, a portion extending angularly from said flat portion and having 65 its end bent back so as to clamp a supported member against the body of the angular portion, and means for preventing spreading of the angular portion with respect to the flat portion under the weight of the supported 70 member.

3. A holder of the class described comprising a flat portion, means for attaching the flat portion in service, a portion extending angularly from the flat portion and 75 having its end bent back and adapted to clamp a supported member against the body of the angular portion, and an element associated with the flat portion and adapted to engage the angular portion to limit the 80 amount of separation of the angular portion with respect to the flat portion.

In testimony whereof, I have signed my name to this specification this 29th day of June, 1927.

LOUIS ANNIN AMES.
